Primary Examiner — Robert M Spear*Assistant Examiner* — Rashida C McCoy(74) *Attorney, Agent, or Firm* — Baker, Donelson, Bearman, Caldwell & Berkowitz, PC; Julie R. Baldridge(57) **CLAIM**

We claim the ornamental design for a spat, as shown and described.

DESCRIPTION

FIG. 1 is a perspective view of a spat showing our new design; FIG. 2 is rear perspective view thereof;

FIG. 3 is a left side elevation view thereof;

FIG. 4 is a right side elevation view thereof;

FIG. 5 is a top view thereof; and,

FIG. 6 is a bottom view thereof.

The broken lines illustrate environmental structure and form no part of the claim.
